UNITED STATES PATENT OFFICE.

GEORGE T. WILLIAMS, HAROLD S. FOSTER, AND NEWTON C. WILKINSON, OF CEDAR RAPIDS, IOWA.

SHOE-FORM.

1,133,077.

Specification of Letters Patent. Patented Mar. 23, 1915.

Application filed November 13, 1914. Serial No. 871,896.

To all whom it may concern:

Be it known that we, GEORGE T. WILLIAMS, HAROLD S. FOSTER, and NEWTON C. WILKINSON, citizens of the United States, all residing at Cedar Rapids, in the county of Linn and State of Iowa, have invented certain new and useful Improvements in Shoe-Forms, of which the following is a specification.

10 This invention relates to means for displaying shoes in store windows and elsewhere; and has for its object to provide a simple device whereby a shoe may be distended so as to present an appearance similar to that it presents when on the foot, as a means for attracting attention to the particular shoe and to other goods in the store.

15 The nature of the invention is fully disclosed in the description and claim following, reference being had to the accompanying drawing, in which—

20 Figure 1 is a view in perspective of a shoe containing one of our improved forms. Fig. 2 shows the form detached. Fig. 3 is a sectional view showing parts of the distending wire and the socket in which its front end is inserted. Fig. 4 is a metal socket to be attached to the molded form inserted in the vamp. Fig. 5 is the sheet metal blank from

25 which said socket is formed.

25 The device is simple, and is briefly described as follows: The numeral 1 refers to a vamp-filling form, which may be molded of leather, papier mâché, or other suitable material, and is in the nature of a partial, skeleton last, designed to plump out the vamp portion of the shoe and give it practically the form it should have when worn. In the case of stiff or "box-toed" shoes this

30 form need not extend entirely to the toe, as indicated by the full outline, but for soft-toed shoes it is desirable that the form have a full toe, as indicated by the dotted line, so that the toe of the shoe is plumped out 35 fully, as well as the rest of the vamp. These forms should vary in size, of course, and also, to a certain extent, as to the style of last according to which the shoe is made.

30 To the front, upper part of the molded form is attached a socket 2, adapted to receive the forward end of a distending wire 3, to be described presently. In practice the socket is formed of sheet metal cut in substantially the shape shown in Fig. 5.

It is bent to form curved wings 4 conforming to the contour of the molded form, to which it is suitably fastened, as by rivets 5. The crimp at 6 forms the back and side walls of the socket, and the tongue 7, bent forward at 8 and upwardly at 9, forms the bottom and front wall of the socket, respectively. The socket would serve fairly well without the tongue, but this is desirable, to protect this part of the molded form from the wear and pressure of the distending wire.

55 The distending wire is best made in substantially the form shown. Just above the end which enters the socket is a slight offset, 10, corresponding to the thickness of the molded form and the tongue of the attached socket, so that the front, curved part of the distending wire runs flush with the front face of the form. Thence upwardly it conforms to the front of the ankle portion of the shoe. At the top, 11, it is preferably made practically straight. The back portion 12 is angled or curved to conform to the back of the ankle and counter, and should terminate in an eye 13, or the like, 60 to prevent any catching or wear on the shoe lining. Normally the distender is considerably wider from front to back than when placed in a shoe, the spring of the wire thus serving to hold the form snugly forward in the vamp, and also to distend the ankle flatwise, giving to the shoe the conventional form which is quite attractive for purposes of display. It is to be noted that the form of the distender is such as to act 65 on the ankle of the shoe almost to the very top, and at the same time leave the wire practically concealed. In practice it is preferred that it be entirely concealed, but in Fig. 1 is shown rather high in order to show 70 it at all without breaking away a part of the shoe.

75 In applying the form to a shoe the vamp-form is first inserted and pressed snugly in place, the shoe being unbuttoned or unlaced. The distender is then sprung inwardly and placed in position, with its front end in the socket. The shoe is then buttoned or laced, and is ready for display, as 80 shown in Fig. 1.

85 Having thus described our invention, we claim:

90 A shoe-form consisting of a vamp-filling

form provided near its rear upper edge with a socket, and a distender for the ankle portion of the shoe composed of a wire conforming at the front and back with the 5 ankle and instep, and with the heel or counter, respectively, the legs of the distender being normally sprung apart, and compressed for insertion in the shoe, and the portion of the front leg inserted in the 10 socket being brought flush with the shoe front close to the vamp-form, so that the

whole front and back of the shoe are held out smoothly by said shoe-form.

In testimony whereof we affix our signatures in presence of two witnesses.

GEORGE T. WILLIAMS.
HAROLD S. FOSTER.
NEWTON C. WILKINSON.
